COMBINED NAIL POLISH CONTAINER AND FINGER REST

Elliott Yellin, 2314 39th Ave., San Francisco,
Calif. 94116

Filed Jan. 12, 1970, Ser. No. 20,876

Term of patent 14 years

Int. Cl. D28—03

U.S. Cl. D86—10

FIG. 1

FIG. 2

FIG. 3

FIG. 4

FIG. 1 is a top plan view of a combined nail polish container and finger rest showing my new design;

FIG. 2 is a side elevational view thereof;

FIG. 3 is a front elevational view taken from the right of FIG. 2; and

FIG. 4 is a longitudinal cross-sectional view.

I claim:

The ornamental design for a combined nail polish container and finger rest, as shown.
